UNITED STATES PATENT OFFICE.

MORGAN E. LASHER AND JACOB V. FORRESTER, OF CHAMPAIGN, ILLINOIS.

HAME-TUG.

SPECIFICATION forming part of Letters Patent No. 359,871, dated March 22, 1887.

Application filed December 27, 1886. Serial No. 232,621. (No model.)

To all whom it may concern:

Be it known that we, MORGAN E. LASHER and JACOB V. FORRESTER, of Champaign, in the county of Champaign and State of Illinois, 5 have invented certain new and useful Improvements in Hame-Tugs; and we do hereby declare that the following is a full, clear, and exact description thereof, reference being had to the accompanying drawings, and to the letters of reference marked thereon, which form 10 part of this specification, in which—

Figure 1 is a side view of a hame-tug embodying our invention and having a portion of a trace attached. Fig. 2 is a central vertical longitudinal section of the same on line $x-x$, Fig. 1. Fig. 3 is a cross-section on line $y-y$, Fig. 1. Fig. 4 is a detail edge view of the tug-hook and its connections with the tug and brace. Fig. 5 is a detail view of the loop E' detached.

This invention relates to improvements in hame-tugs, the object being to provide a tug that can be quickly and readily attached to or detached from its hame, and which can be employed in connection with all sizes and styles of draft-harness—both slip and long tug harness—so that the dealers will not be obliged to keep in stock all the different sizes of tugs.

The invention consists in the construction 30 and novel arrangement of parts hereinafter described, and shown in the drawings.

Referring by letter to the drawings, B designates a hame-tug, composed, in this instance, of the usual leather fold, C , having the 35 trace-loop c standing from it at a proper point, and having the bail of the front portion of the trace-buckle journaled in the bend at its rear end.

D designates any ordinary trace, and E is 40 the hame-clip for connecting the tug to the ring of its hame A , as shown in dotted lines in Fig. 1.

H designates the front hook portion of the clip, and is of general oval form and concaved 45 on its inner face, as shown, so that it will lie snugly upon the convex surface of the collar, to which its hame is attached, and not wear the collar by undue pressure thereon, as it would if its face were straight. The part H 50 has its outer end extended into a hook, h , which is bent outward and rearward upon

part H , and has its point entering the opening between the sides of said part H and within or below the outer surface of said sides, as shown clearly in Fig. 2. This hook h is adapted 55 to engage the hame ring or staple a (shown in dotted lines in Figs. 1 and 2) of its hame A , and engage and disengage these parts, to do which it is necessary to turn the hame or tug so that the ring a and hook h will lie in the 60 same horizontal plane, so that when attached, as shown in Fig. 1, it will be impossible for the hook to become detached in ordinary use. The rear ends of the sides of the part H are connected by a flat cross-bar, I , beyond which bar 65 the sides extend into the arms $h' h'$, which are connected by a bar, I , that forms the bearings or connections of part H with part E' of the clip. The arms $h' h'$ are widened vertically 70 above bar I , as shown, and their upper or outer angular corners form shoulders $i i$, for a purpose hereinafter shown, while their lower or inner corners are rounded.

E' designates the rear portion of the clip, and consists of a metallic plate bent upon itself in a U shape, and journaled at its bend upon the bar I of part H , as shown, forming a 75 toggle-joint with said part H .

In order to prevent the parts E' and H of clip E , united as described, from turning inwardly when in use, and thereby wounding or galling the animal in harness, we widen the outer leaf, e , of part E' , near the bend of said leaf, so that the outer edges of the same will be flush with the outside edges of arms h' ; or, in 85 other words, make the portion of leaf e as wide as portion H . By doing this we form shoulders i' on the leaf e , which shoulders will engage the shoulders i on arms h' when the parts H and E' are in ordinary working position, 90 and will prevent the said parts from turning inward at their joint, but will not hinder their turning outward. The bend of part E' is preferably wide enough to fit snugly between the side bars of part H , so that there will be no 95 vertical play of the said parts upon each other. The front end of fold C enters between the leaves of part E' , and is secured thereto by means of suitable bolts or rivets, as shown. When metal tugs are used, the loop E' can be 100 attached to the metal body of the tug, similarly to its attachment to fold C , or the loop

E' may itself be enlarged into the tug-body, as is evident. The outer end or leaf, e, of part E' is preferably formed into the parts e'e', the part e' being next to the bend of the plate, 5 and extends rearward about half the length of plate e, and the part e' being narrower than the part e', as shown, and extending from said part to the end of the plate. On the inner surface of each of said parts e'e', or the 10 surface adjacent to fold C, is formed a transverse groove, e², as shown. The said grooves are adapted to hold the shanks of loops F, which loops embrace the front end of the trace D, as shown. By having the grooved leaf of 15 part E' made of varying width, as described, different-sized loops F, for different-sized traces, can be attached to the tug, as is evident, and still present a neat appearance.

We are aware that a hook similar to hook h 20 has been used, therefore we do not claim such broadly; but,

Having described our invention, what we do claim is—

1. A hame clip composed of a plate portion 25 bent as described and adapted to be secured to the front end of a tug, and provided at its bend with shoulders, and a hook portion having its rear transverse bar journaled in the bend of the plate, and having the rear ends of 30 its side bars widened into shoulders which will engage the shoulders of the plate portion, thus preventing the two said portions bending inward on each other, all substantially as described.

35 2. The combination, with a hame-tug, substantially as described, of a hame-clip composed of the loop E', having shoulders i' formed at its bend, as described, and the part H, hav-

ing hook h, and widened extended ends h', carrying a bar, I, by which part H is journaled on part E', and shoulders i formed on the ends h', and adapted to engage the shoulders i' and prevent the parts E' and H from turning inward, all substantially as and for the purpose set forth. 45

3. In a hame-tug, a jointed hame-clip having a plate portion, bent as described, secured to the front end of the body of the tug, and having its outer leaf, which lies upon the outer face of the said tug-body, made of varying 50 width and provided on its under surface with transverse grooves to receive and hold the shanks of suitable trace-loops, substantially as described.

4. The herein-described hame-tug, composed of the leather fold C, provided with the usual leather trace-loop, and the hame-clip having the part E' secured to the front end of the fold, and provided with shoulders i', and having its outer leaf, e, made of varying width 60 and provided with grooves e² on its inner surface, and the part H, concaved on its inner surface, having its rear bar journaled in the bend of the plate portion, and provided on its front end with the hook h and at its rear with shoulder i, adapted to engage the shoulders i' and prevent the parts E' and H turning inward on each other, all substantially as described. 65

In testimony that we claim the foregoing as our own we affix our signatures in presence of 70 two witnesses.

MORGAN E. LASHER.
JACOB V. FORRESTER.
